US00D924196S

(12) **United States Design Patent** (10) **Patent No.:** **US D924,196 S**
(45) **Date of Patent:** **** Jul. 6, 2021**

(54) **DOCKING STATION WITH A SPEAKER**

(71) Applicant: **BIZLINK INTERNATIONAL CORPORATION**, New Taipei (TW)

(72) Inventor: **Shih-Yung Wang**, New Taipei (TW)

(73) Assignee: **BIZLINK INTERNATIONAL CORPORATION**, New Taipei (TW)

(**) Term: **15 Years**

(21) Appl. No.: **29/724,578**

(22) Filed: **Feb. 18, 2020**

(51) LOC (13) Cl. **14-03**

(52) U.S. Cl.

USPC **D14/149**

(57) **CLAIM**

The ornamental design for a docking station with a speaker, as shown and described.

DESCRIPTION

FIG. 1 is a perspective view of a docking station with a speaker, showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is another perspective view thereof; and,
FIG. 9 is an operational perspective view showing one end of a cable of the docking station with a speaker detached from a casing of the docking station with a speaker.
The broken lines shown in FIGS. 1-6 and 8-9 illustrate portions of the docking station with a speaker that form no part of the claimed design.

1 Claim, 9 Drawing Sheets
